(57) **CLAIM**

The ornamental design for an automotive wheel, as shown and described.

DESCRIPTION

FIG. 1 is a front perspective view of an automotive wheel showing my new design;

FIG. 2 is a front view thereof;

FIG. 3 is a top view thereof;

FIG. 4 is a side view thereof;

FIG. 5 is a bottom view thereof;

FIG. 6 is a side view thereof, opposite FIG. 4; and,

FIG. 7 is a rear view thereof.

The broken lines in the drawings illustrate portions of the automotive wheel and form no part of the claimed design. The stipple pattern indicates areas that contrast versus the other non-stippled areas.
